PRESSURE CONTROLLING DEVICE FOR
GASOLINE PUMPS

David McCormick, Dunmore, Pa.

Application August 15, 1934, Serial No. 739,975

6 Claims. (Cl. 221—95)

My invention relates to pressure control means for liquid dispensing apparatus and more particularly to an arrangement adapted to compensate for excessive pressures due to expansion in gasoline pumps.

In conventional gasoline pumps, it is well known that the pressure line, including the visi-glass, meter unit, discharge base and associated pipes, and connections remain filled with gasoline after a quantity of gasoline has been dispensed. The pumps are generally exposed to atmospheric temperature and since gasoline has a high coefficient of expansion, it readily expands when subjected to the temperature differential existing between the comparatively cool zone in which gasoline is stored and the atmosphere surrounding the pump. If the pumps are exposed to the sun, and they usually are, according to present practice in connection with the dispensing of gasoline at service stations, the rate of expansion is considerably increased.

When the temperature of the gasoline is raised to that of the atmosphere and the gasoline expands, there is a corresponding increase in pressure which is transmitted directly to the pressure line. The resultant increase in pressure is of such magnitude that it frequently causes breakage in some part of the pressure line; there is also considerable danger because of the fire hazard as the result of leakage of gasoline in and around the pump unit.

It will be appreciated that the expense, incident to the servicing of pumps which are rendered inoperative because of breakage in the pressure line due to expansion of the gasoline, is of considerable importance. The unit cannot be used while repairs are being made and even after it is placed in working order again the parts are still exposed to excessive pressures developed by the expansion of the gasoline.

Heretofore, it has been proposed to control or compensate for the expansion of the gasoline by means of vents and float valves inserted in various positions in the pressure line. It has also been suggested to use an expansion chamber or storage tank associated with the pressure line adapted to prevent excessive pressure from developing in the system, however, the prior art devices, insofar as I am aware, fail to provide a satisfactory and economical arrangement to prevent increased pressure in the pressure line of gasoline pumps.

According to my invention means are provided for automatically and instantaneously releasing the pressure from the pressure line of a

gasoline pump, caused by the expansion of the gasoline. The expansion eliminator is easily and quickly applied to conventional pumps and does not interfere in any way with the normal operation of the pump when it is desired to dispense gasoline therefrom.

An object of the invention is to provide an improved pressure control arrangement for gasoline pumps wherein pressure due to the expansion of the gasoline is automatically relieved. 10

Another object of the invention is to provide an expansion eliminator for gasoline pumps, by means of which any increase in the normal pressure of the pump due to expansion of the gasoline line is automatically and instantaneously reduced.

Yet another object of the invention is to provide an improved expansion eliminator for gasoline pumps wherein gasoline which is withdrawn for the purpose of relieving the pressure is returned to the system when the pump is operated, for dispensing purposes.

Still another object of the invention is to provide a pressure control device for gasoline pumps, which is strong and sturdy in construction, consisting of but few parts and not liable to get out of order even after long and continued use.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawing:

Figure 1 is an elevational view showing my improved expansion eliminator associated with a gasoline pump unit.

Fig. 2 is a sectional view of one of the valve structures used in connection with the expansion eliminator; and

Fig. 3 is a perspective view of a check valve.

Referring to the drawing and more particularly to Figure 1 thereof, there is shown a gasoline pump unit comprising a base 1, a support casing 2, and a cover or top 3. Within the cas-

ing there is mounted a suitable pump designated generally by numeral 4 which is connected by means of a fitting 5 to a supply pipe 6 associated with a liquid storage tank 7. The discharge side of the pump is connected through medium of suitable pipes, forming a discharge line to the visi-glass 8, from which the liquid passes to a discharge hose 9. Intermediate the discharge side of the pump and the discharge hose, there 10 is mounted a metering device, not shown, for measuring the quantity of gasoline dispensed.

In the operation of the pump unit, so far described, when the outlet valve on the discharge end of the hose is closed, a slight pressure occurs in the discharge line and this pressure increases if the pump continues to operate. After the pressure reaches a certain value, a bypass valve in the pump unit or the valve applied to the loading or dispensing line, opens 15 and permits the gasoline to revolve through the system and back through the pump. In order to maintain sufficient vacuum or suction on the unit, the bypass must be provided with a suitable spring action sufficient to close the valve 20 when the pump is stopped, so that there is always a positive working pressure on the unit. When gasoline withdrawn from the storage tank is permitted to stand in the pump exposed to the atmosphere, the body of gasoline in the 25 meter unit, the visi-glass, and in all of the associated pipes and discharge hose, expands due to the temperature differential. The increased pressure caused by the expansion of the gasoline causes damage to the gaskets, the discharge 30 hose and associated fittings, and tends to seep through packing nuts placed between the various 35 connections.

In order to reduce the pressure in the discharge line and prevent damage to the pump 40 caused by the breakage of any of the vital parts, I have provided an expansion eliminator comprising an overflow connection 10 in the form of a pipe connected between the discharge side of the pump 4 and the visi-glass 8. Pipe 10 is connected to the top of the glass 8 and is provided with a valve 11, normally in the open 45 position, connected directly to the top of the glass and a check valve 12 near its connection to the suction side of the pump. Intermediate 50 the ends of the tube, the pipe is coiled as at 13 to provide a storage space for any gasoline which may overflow from the visi-glass.

In the operation of the device, assuming that the pump is at rest, increased pressure, due to 55 the expansion of the gasoline which remains in the metering unit, the visi-glass and the discharge line including the discharge hose, forces gasoline from the visi-glass up through valve 11 and into the overflow tube 10. When the 60 pump is operated to dispense gasoline, valve 11 is closed and valve 12 is opened whereby the gasoline which has overflowed into the tube and is contained in coiled portion 13 is withdrawn into the pump. As soon as the pump stops, the 65 valve 12 is closed and valve 11 is opened.

Referring to Figure 2, I have shown a detail view of valve 11, comprising a body portion 14 having a valve stem 15 slidably mounted therein. It will be noted that the stem 15 is of slightly 70 smaller diameter than the opening 16 formed in the body portion of the valve and that the end of the body portion is recessed as at 17 to form a seat for the head of the valve 18. The body of the valve is threaded as at 19 and 20, 75 portion 20 being adapted to thread into the top

of the visi-glass and portion 19 being arranged to receive a fitting 21, whereby the pipe 10 is connected to the valve. It will be noted that when the pump is at rest, that the valve stem 15 of valve 11 is in its lowermost position and the space 16 between the stem of the valve and the body portion 20 allows passage of gasoline from the glass to the overflow tube 10.

Referring to Figure 3, I have shown a view of the check valve 12 which is mounted between the suction side of the pump and the connection to the overflow tube 10. This valve is of conventional construction and comprises a body portion 22 having a pivoted flap 23 adapted to open when a suction is applied to connection 24 15 when the pump is operated.

While I have shown and described the preferred embodiment of my invention, I wish it to be understood that I do not confine myself to the precise details of construction herein set forth, by way of illustrations, as it is apparent that many changes and variations may be made therein, by those skilled in the art, without departing from the spirit of the invention, or exceeding the scope of the appended claims. 25

In the claims:

1. In a liquid dispensing apparatus, including a pump, a source of liquid supply, and a discharge line for the liquid, a pressure control device comprising a tube between the discharge line and the suction side of the pump, said tube being formed with a coiled portion to accommodate the overflow liquid, a valve means attached to one end of the tube to control the flow of liquid thereto and separate valve means at the other end of the tube to control the flow of said liquid to the pump. 30

2. In a liquid dispensing apparatus, including a pump, a source of liquid supply, and a discharge line for the liquid, a pressure control device comprising a tube between the highest point on the discharge and the suction side of the pump, said tube being formed with a coiled portion to accommodate the overflow liquid, the tube being provided with a valve to control the flow of liquid thereto and a separate valve to control the flow 45 of said liquid to the pump.

3. In a liquid dispensing apparatus, including a pump, a source of liquid supply and a discharge line provided with a visi-glass, a pressure control device comprising a tube connected between the top of the visi-glass and the suction side of the pump, said tube being provided with valve means to control the flow of liquid thereto from the glass and separate valve means to control the flow of said liquid to the pump. 50

4. In a liquid dispensing apparatus, including a pump, a source of liquid supply and a discharge line provided with a visi-glass, a pressure control device comprising a tube connected between the top of the visi-glass and the suction side of the pump, said tube being formed with a coiled portion to accommodate the overflow liquid, a valve means attached to one end of the tube to control the flow of liquid thereto, and separate valve means at the other end of the tube to control the flow of said liquid to the pump. 60

5. In a liquid dispensing apparatus, including a pump, a source of liquid supply, and a discharge line for the liquid, a pressure control device comprising a tube between the discharge line and the suction side of the pump, said tube being formed with a coiled portion to accommodate the overflow liquid, a valve attached to one end of the tube to control the flow of liquid thereto, said valve being normally in the open position and a 70 75

- second valve at the other end of the tube to control the flow of said liquid to the pump, said second valve being normally in the closed position, the first mentioned valve being adapted to close and said second mentioned valve being adapted to open whereby the overflow liquid is withdrawn from the coiled portion of the tube when the pump is operated to dispense liquid.
6. In a liquid dispensing apparatus, including a pump, a source of liquid supply and a discharge line provided with a visi-glass, a pressure control device comprising a tube connected between the

top of the visi-glass and the suction side of the pump, said tube being provided with a valve to control the flow of liquid thereto, said valve being normally in the open position and a second valve to control the flow of said liquid to the pump, said second valve being normally in the closed position, the first mentioned valve being adapted to close and said second mentioned valve being adapted to open, whereby the overflow liquid is withdrawn from the tube when the pump is operated to dispense liquid.

DAVID McCORMICK.
